UNITED STATES PATENT OFFICE

TELFORD MACLENNAN, OF HAMILTON, NEW ZEALAND

FURNACE

Application filed June 14, 1928, Serial No. 285,287, and in New Zealand July 15, 1927.

This invention has been devised with the object of providing a construction of domestic or other furnace that is designed to employ a forced draught and therefore is made adaptable to the burning of fine coal slack or other low grade fuel, as the fuel for the fire.

The invention consists in the construction of the furnace with a bottom grate made so that while allowing for the draught passing 10 freely upward through it, it will serve to retain the fuel within the grate. The invention also is concerned with provision for the automatic supply of fuel to the fire, as consumption takes place.

15 The invention comprises generally the combination with a furnace designed to be acted upon by a forced draught, of inclined fuel supply passages that automatically feed the fuel to the furnace, as that within it is consumed. It also comprises the use within such furnace, of a fire grate constructed to support upon it finely divided fuel without liability of the fuel falling through and at the same time to provide for the passage of the forced draught up through the grate over the whole of its area.

The invention may be given effect to in the manner shown in the accompanying drawings which illustrate a combined furnace and fuel supply passages embodying the features of the invention.

In such drawings:—

Figure 1 is a plan of the device.

Figure 2 is a sectional plan of the lower or furnace portion thereof and taken on the line 2-2 of Figure 3.

Figure 3 is a cross sectional elevation of the device.

Figure 4 is a side elevation thereof, half being in section.

In the form of the invention shown the apparatus of the present invention comprises a single metallic casing A of rectangular form and so shaped as to provide a lower fuel combustion chamber B, and an upper fuel supply chamber C of larger surface area than the combustion chamber, the sides of which casing A taper inwards and downwards to the sides of the combustion chamber B. The fuel supply chamber is divided throughout its length

by any approved divisional member D, such as will on each side, form with the tapering side of the casing, an inclined passage E leading into the top of the combustion chamber on that side.

Conveniently the said dividing member D may be a water boiler such as that shown in the drawings, having all the usual circulating and supply connections and which by extending along above the combustion chamber will be heated by the fire therein. The underside of the boiler is concaved and at one end the concave space connects with a flue F leading from the back of the casing so that the products of combustion from the chamber B may be collected and led off through the flue. 65

The top of the casing being filled with finely divided coal, such fuel will gravitate down through both passages E into the chamber B beneath, as the fuel in such chamber is consumed, and thereby keep the chamber automatically supplied so long as a supply is maintained within the fuel supply chamber C. 70

The furnace grate, as shown, is formed by a plate *G* that is supported at the required height within the casing *A* and is made with longitudinal openings *H*, and fire bars *J*, of *Z* or *T* cross sectional shape, supported to extend along within or beneath such openings so as to divide them up into a number of different slots each of which is underlaid at a lower level by a member of the fire bars. This arrangement leaves free air passages through the grate, while preventing the fuel from falling through it. 75 80 85

The sides and ends of the grate may have fire-clay blocks K arranged thereon to concentrate the fire on to the middle portion of the grate. Also the grate length may be divided into two by means of a fireclay block M extending along the middle line of the grate. These may however be dispensed with if so desired.

The grate may also be formed in other ways such as to ensure of the air passages of the 95 nature described, being formed through the grate.

The draught chamber, beneath the grate, is enclosed and the forced air draught led into it through the conduit N. Other ways of ob- 100

taining this updraught may however be provided.

It will be seen that by the construction shown, a furnace is produced that is suitable for the burning of finely divided coal fuel or slack, that needs no attention in the feeding of the fuel to the fire after the supply chamber is filled, that will burn freely by reason of the forced draught and in addition, heat a supply of water if so desired.

10 I claim:—

1. A furnace comprising a casing, a fire grate arranged in said casing, a domed member disposed in said casing above said grate and dividing the portion of said casing above said grate into a fuel supply chamber and a fuel combustion chamber communicating with one another, means for supplying a current of air to the under side of said grate, and means for withdrawing the gases of combustion.

2. A furnace comprising a hopper shaped casing, a fire grate arranged in the lower portion of said casing, a domed member disposed in said casing above said grate and dividing the portion of said casing above said grate into a fuel supply chamber and a fuel combustion chamber, said domed member having portions thereof spaced from the side walls of said casing and forming therewith feed passages leading from said fuel supply chamber to said fuel combustion chamber, means for supplying a current of air to the under side of said grate, and means for withdrawing the gases of combustion from said fuel combustion chamber.

3. A furnace comprising a hopper shaped casing having tapering side walls, a fire grate arranged in the lower portion of said casing, a hollow domed member disposed in said casing above said grate and dividing the portion of said casing above said grate into a fuel supply chamber and a fuel combustion chamber, said domed member having side walls spaced from the side walls of said casing and forming therewith inclined feed passages leading from said fuel supply chamber to said fuel combustion chamber, means for supplying a current of air to the under side of said grate, said grate being adapted to permit the passage of air but to prevent the falling of fuel therethrough, and means communicating with said fuel combustion chamber for withdrawing the gases of combustion.

4. A furnace comprising a hopper shaped casing, a fire grate arranged in said casing, a domed member disposed in said casing above said grate and dividing the portion of said casing above said grate into a fuel supply chamber above said member and a fuel combustion chamber beneath said member, said domed member having side walls spaced from the side walls of said casing and forming therewith feed passages leading from said supply chamber to said combustion

chamber, means for supplying a current of air to the under side of said grate, and means communicating with the chamber beneath said domed member for withdrawing the gases of combustion.

70 In testimony whereof, I affix my signature.

TELFORD MACLENNAN.
